4 Claims. (Cl. 89—1)

1

The present invention relates to gun chargers for automatic machine guns and the like, and more particularly to a method and apparatus for controlling the operation of such gun chargers.

In automatic machine guns, for example, of the "Browning" type, the firing pin may be released either mechanically or electrically to fire a cartridge in the cartridge chamber of the barrel of the gun. The recoil caused by the explosion of the cartridge causes a bolt mechanism or charging mechanism to be moved rearward with respect to the cartridge chamber. Upon rearward movement, the charging mechanism extracts the case of the fired cartridge from the chamber and moves a cartridge belt or clip one notch to present a succeeding cartridge adapted to be inserted into the chamber. After the charging mechanism has been moved to its rearmost position and has been fully retracted, it is returned or moved forwardly by a strong spring or the like. In the course of its return stroke the charging mechanism ejects the case of the fired cartridge from the gun and inserts the succeeding cartridge into the chamber.

While the firing pin is released, the gun fires each time the charging mechanism returns to its extreme forward position. If no trouble develops, the cycle of operation of the charging mechanism may be repeated at a rate of between 400 and 1000 times per minute.

Once the gun has been provided with a supply of ammunition and has been fired, firing should continue automatically until the supply of ammunition is exhausted, unless any one of a number of possible difficulties occurs. For example, a cartridge may fail to explode or may fail to develop a recoil force sufficient to move the bolt or charging mechanism through the extracting, ejecting and loading cycle. Also, the charging mechanism may fail to extract the empty case of a fired cartridge, which may jam in the chamber and resist removal on the first attempt; or the charging mechanism may fail to properly advance the cartridge belt or clip one notch, whereby difficulty may be encountered in inserting the succeeding cartridge and ejecting the case of the fired cartridge. In the event that the bolt or charging mechanism fails to function properly for any of the foregoing reasons or other difficulties, the gun will cease firing, and it will become necessary to recock the bolt or charging mechanism by moving it rearwardly and then releasing it to complete the extracting, ejecting and reloading operations and restore firing of the gun.

Heretofore, devices known as gun chargers have been chosen for purposes of illustration and de-

2

(which are not to be confused with the bolt or charging mechanism) have been employed for mechanically recocking or initiating the operation of the charging mechanism. None of these devices has been found fully satisfactory, because the control means therefor were unreliable in performance, and relatively slow in response to slowing down or stopping of the firing of the gun, whereby relatively long delays were occasioned before the gun was restored to its normal firing action.

The present invention aims to provide a rapid and reliable method and apparatus for detecting and controlling the operation of the gun charger of machine guns and the like. The invention further aims to provide an improved, simple and practical detecting and controlling apparatus which is light in weight, occupies a minimum amount of space and is constructed of a minimum number of parts.

An object of the invention is to provide a detecting and controlling apparatus which provides an electric current of a predetermined value in response to the normal movement of the charging mechanism adapted to prevent the actuation of the gun charger, whereby, in the event the charging mechanism slows down substantially or stops, current of a sufficient magnitude fails to be provided and the gun charger is no longer prevented from being actuated.

Another object is to provide a detecting and controlling apparatus in accordance with the foregoing; wherein an electric current is supplied for controlling the actuation of the gun charger, and an electric current is generated in response to the normal firing of the gun which opposes the supplied current so as to prevent operation of the controlling apparatus of the gun charger during the normal firing of the gun.

Another object is to provide a method of detecting the slowing down or stoppage of the charging mechanism, in accordance with the foregoing objects.

A further object consists in the combination and arrangement of parts whereby the foregoing objects and advantages may be accomplished.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has

scription and is shown in the accompanying drawings, forming a part of the specification, wherein:

Figure 1 is a diagrammatic side view of a machine gun having a gun charger attached thereto.

Figure 2 is a diagrammatic view, partly in section, of the essential operating parts of the gun charger and a detecting and controlling device, illustrating an embodiment of the invention.

Figure 3 is a wiring diagram of an electric circuit for operating the detecting and controlling device, in accordance with the invention.

Figure 4 is a wiring diagram of an electric circuit, illustrating another embodiment of the invention.

Referring to the drawings, and more particularly to Figure 1, there is shown a machine gun, for example, of the "Browning" type which, generally comprises a barrel assembly 8 and a bolt mechanism or charging mechanism 9 (not shown in detail), located in a housing or casing 10. The charging mechanism is of the usual design and comprises a number of slidably movable and reciprocating parts which are adapted to be moved rearwardly or retracted by the recoil resulting from the explosion of the fired cartridges, and adapted to be moved forwardly or returned by resilient means, such as a spring 11 or the like which becomes energized by the recoil. During the reciprocation of these parts, the normal operating cycle of the gun is carried out. This cycle comprises the steps of removing a cartridge from the cartridge belt and inserting it into the chamber of the barrel, firing the cartridge, withdrawing the empty cartridge case from the chamber, moving the belt one notch, and ejecting the cartridge case from the housing 10. Since the construction and operation of such a charging mechanism is well known to those skilled in the art, and since the charging mechanism per se does not constitute a part of the present invention, a detailed illustration and description thereof is not believed to be necessary.

In the event the normal operating or firing cycle of the gun is interrupted and firing ceases, the gun must be recharged or recocked before it will operate automatically again. To accomplish this, a gun charger 12, suitably encased, may be attached to either side of the gun casing or housing 10 and may be operatively connected to the charging mechanism by a bolt or stud 14.

The stud or bolt 14 reciprocates with, and may be part of, the charging mechanism, and is adapted to extend through an elongated slot 15 in the housing and extend into the gun charger casing.

The gun charger 12, preferably, is pneumatically operated by a fluid pressure medium, such as high pressure carbon dioxide, compressed air or any suitable gas stored in a container 16. The pressure medium is supplied to the gun charger by a hose or tube 17 connected to a valve 18 which is adapted to be operated by suitable devices (not shown), actuated in response to the failure of the charging mechanism to reciprocate in its normal manner. Suitable electrically operated devices may be utilized for detecting the stoppage or slowing down of the charging mechanism, which may be associated with the charging mechanism and the gun charger. These detecting devices may be electrically connected to a control panel, a source of electrical energy, and other electrical devices by means of a cable 19 containing electrical conductors.

In Figure 2, the essential operating parts of the gun charger 12 are illustrated diagrammatically. The gun charger is provided with a fluid

pressure medium operated ram or plunger mechanism 20, comprising a cylinder 21 and a piston assembly including a piston 22 and a piston rod 23 slidably mounted in the cylinder. The piston rod is adapted to extend out of one end of the cylinder, and carries a ramming head 24 positioned for movement in the path of a rider assembly 25 connected to the reciprocating bolt or stud 14 of the charging mechanism.

When the ram or plunger mechanism 20 is operated, the piston rod 23 moves out of the cylinder, and the ramming head is adapted to engage the rider assembly 25 and move it toward the left, that is, in rearward or retracted position with respect to the gun. The piston assembly, including the piston rod and the piston, and the ramming head may be returned to their initial position, as shown in Figure 2, by resilient means such as a spring 26 mounted in the cylinder 21.

The end of the cylinder opposite the end from which the piston rod is adapted to extend is provided with a port 27 for admitting the pressure medium in back of the piston 22, and for permitting the pressure medium to be exhausted. A tube or conduit 29 connects the port 27 to the valve 18, which is adapted to control the admission of the pressure medium to the cylinder 21 and the exhaust of the medium to the atmosphere.

The valve 18 comprises an inlet 30 in communication with the hose 17 supplying the pressure medium from the container 16; a valve seat 31 adjacent the inlet 30; a valve chamber 32; a port 34 in communication with the valve chamber 32 and leading to the tube 29; and an exhaust port or vent 35 in communication with the valve chamber 32 and having an annular seat 36 facing the inlet valve seat 31. A suitable valve member 37 is slidably mounted in the valve chamber 32 for controlling the admission and exhaust of the pressure medium. The valve member 37 may have a sealing surface 38 at one end for seating on the valve seat 31, and may have a sealing surface 40 at its other end for seating on the valve seat 36 of the exhaust port when the surface 39 is unseated. The pressure medium at the inlet 30 tends to unseat the valve member 37 from the inlet seat 31 and to cause the surface 40 of the valve member to abut the exhaust port seat 36.

In order to normally close the inlet 30, there is provided a stem 41, slidably mounted in the valve body and extending through the exhaust port 35, having one end thereof attached to the valve member 37 and having its other end extending outwardly of the valve body; and a bell crank lever 42 for engaging the outwardly extending end of the stem 41 and moving it inwardly into the valve body to cause the surface 39 of the valve member 37 to be moved against its seat 31. The lever 42 is pivoted at 44, and has an arm 45, engaging the free end of the stem 41, and a second arm 46, held downwardly by a spring 47, or the like, whereby the arm 45 is maintained in a position to urge the stem 41 into the valve body. Preferably, a solenoid 50, or the like, is provided for rocking the arm 46 upwardly in opposition to the spring 47, whereby the arm 45 is moved away from the stem 41 to permit the valve member to move away from the inlet seat and admit pressure medium to the cylinder 21.

The lever 42 may be further controlled to effect operation of the valve in predetermined re-

lation with the movement of the ram upon actuation thereof. For example, it may be desirable to maintain the valve 12 open until the bolt 14 has been moved by the ramming head into a position to reenergize the charging mechanism of the gun. This may be accomplished by suitable devices illustrated diagrammatically herein as comprising a lever 51 pivoted at 52 adapted to be engaged by a projection 54 on the rider assembly when the bolt has been fully retracted, and a connecting rod 55 pivotally connected to the lever 51 and the arm 45 of the lever 42 adapted to effect return of the lever to its initial valve closing position upon engagement of the lever 51 by the projection 54. Since such devices do not constitute a part of the present invention, a detailed description thereof is not necessary.

In order to effect operation of the valve controlling solenoid 50 in the event of stoppage or slowing down of the reciprocating bolt 14 of the gun charging mechanism, suitable electrical detecting and controlling circuits are provided, which will now be described. In accordance with the invention, an electric current of a predetermined magnitude is generated during the normal reciprocating movement of the bolt 14, and the failure of current of such a magnitude to be generated due to the stoppage or slowing down of the bolt 14 determines the operation of the solenoid 50.

The current may be generated by any suitable means operatively associated with the rider assembly 25 connected to the bolt 14. For purposes of illustration, the generating means may comprise a stationary, elongated, inductively wound coil 60 extending lengthwise with respect to the charging mechanism of the gun, and a permanent magnet 61 adapted to be reciprocated within the coil by having one end thereof secured to a bracket 62 carried by the rider assembly 25. This arrangement is adapted to generate in the coil 60 a current of the alternating or rapidly reversing type, and the generated current is adapted to be conducted to rectifying means by wires or conductors 64 and 65 connected to the respective terminals of the coil 60.

As illustrated more particularly in Figure 3, the alternating type current is adapted to be rectified to provide a direct or continuous type current, by a suitable rectifying circuit such as a bridge rectifier 66, or the like, having terminals 67 and 68. It will be understood, of course, that a direct or continuous type current may be provided by operatively connecting a direct current generator, or the like, to the reciprocating bolt 14, for instance, by suitable drive means for translating reciprocating rectilinear motion into rotary motion.

In Figure 3, a detecting and controlling circuit is shown which comprises a source of electrical current, such as a battery 70, the current of which will be referred to herein as the "supplied current"; the current generating means, including the coil 60, the magnet 61 and the bridge rectifier 66 for providing the "generated current"; a delayed action relay 71 or the like for operating a switch 72 for controlling the energization of the valve solenoid 50; suitable resistance elements 74, 75 and 76 adapted to be utilized for balancing the voltages of the supplied and generated currents; and a switch 77 which is closed during the firing of the gun. This switch 77 may be associated with the trigger of the gun, so that operation of the trigger closes the switch.

In accordance with the invention, the fore- 75 the voltages E and e.

going elements are arranged in the circuit so that the voltage of the supplied current is adapted to be opposed by the voltage of the generated current, to thereby prevent or decrease the flow of current through the relay 71 and prevent operation thereof to close the solenoid switch 72. To accomplish this, one of the terminals of the battery is electrically connected to the terminal of the like sign of the rectifier. For example, as shown, the negative (-) terminal 78 of the battery 70 may be connected, by a wire 79, to the negative (-) terminal 68 of the bridge rectifier, and the positive (+) terminal 80 of the battery may be operatively connected to the positive (+) terminal 67 of the bridge rectifier as about to be described.

A wire 81 connects the terminal 80 to one terminal 82 of the switch 77; a wire 84 connects the other terminal 85 of the switch 77 to one terminal 86 of the resistance element 74 which serves to reduce the voltage of the battery current at the other terminal 89 of the resistance element 74; a wire 87 connects the other terminal 89 of the resistance element 74 to one terminal 90 of the relay 71; and a wire 91 connects the other terminal 92 of the relay to the terminal 67 of the bridge rectifier 66. One terminal 93 of the relay controlled switch 72 is connected to the battery terminal 80 through the wires 81 and 84 and the switch 77.

The resistance element 75 is connected in the battery circuit by connecting one terminal thereof to the terminal 89 of the resistance element 74 and connecting the other terminal thereof to the wire 79 at 94. The resistance element 76 is connected across the bridge rectifier by connecting one terminal thereof to the wire 91 at 95 and connecting the other terminal thereof to the wire 79 at 96. With the foregoing arrangement, while the gun is firing normally, the voltage e of the generated current across wires 79 and 91 is substantially equal to the voltage E of the supplied current across the wire 81 and the wire 79. By reason of the fact that voltages e and E are substantially equal and in opposition, no current will flow through the relay 71 whereby the relay is prevented from operating the switch 72. The generated current i will be dissipated by the resistance element 76, while the supplied current I 50 will be dissipated by the resistance element 75.

In the event the gun slows down or stops firing, generation of current will decrease in magnitude or cease, whereby the circuit will no longer be affected by the generated current to prevent operation of the relay 71. As the potential across the terminals 95 and 96 drops to a value less than that across terminals 89 and 94, an equalizing current is adapted to flow through the relay 71 to effect operation of the switch 72. When the switch 72 is closed, current is adapted to be supplied to the solenoid 50 by a pair of conductors or wires 97 and 99, the wire 97 being connected to the battery terminal 78 and the wire 99 being connected to the battery terminal 80 through the wire 81, switch 77, wire 84 and switch 72.

In the foregoing described circuit, the battery voltage across its terminals 78 and 80 normally exceeds the rectified generated voltage across the terminals 67 and 68, and hence the resistance element 74 is utilized to equalize the effective battery voltage E and the generated voltage e. While a fixed resistance element 74 is shown, it will be understood that a variable resistance element may be substituted therefor to accurately balance

It will also be understood that the current generated may have a voltage equal to the voltage of the battery current across the battery terminals. This would eliminate the necessity for a compensating resistance element 74.

It is also contemplated that the voltage of the generated current might exceed the voltage of the battery or supplied current. Thus to prevent the voltage of the generated current from overcoming the voltage of the supplied current and causing a portion of the generated current to flow through the relay and effect operation thereof, the relay 71 may be of the polarized type, and may be so connected in the circuit that only the flow of battery current in one direction there-through will close the switch 72 associated therewith, and that the flow of generated current in the other direction therethrough will not effect operation of the switch 72. This type of relay eliminates the need for very accurately balancing the effective supplied voltage E and the generated voltage e , provided of course that the voltage e only slightly exceeds the voltage E during normal firing of the gun.

As mentioned herein, the relay, preferably, is of the slow operating or delayed action type which is affected by the flow of current therethrough for a predetermined period, but is unaffected by transient currents of a duration less than the predetermined duration.

In Figure 4, a modified circuit is illustrated wherein current is prevented from being supplied to the gun charger controlling solenoid 50 during normal firing of the gun, by providing an electric current during the normal motion of the bolt mechanism or the like which affects or energizes electrical means, such as a holding relay, which holds open a switch for supplying current to the solenoid 50. This circuit may comprise a battery 70', having a pair of terminals 78' and 80', a wire 97' connecting the terminal 78' to one terminal of the solenoid 50, and a wire 99' connecting the other terminal of the solenoid to the terminal 80' by means of suitable switches and conductors about to be described.

These means include a trigger switch 77' having a terminal 82' connected by a wire 81' to the terminal 80'; and a switch 101 normally held in open circuit position by a spring 102 and adapted to be moved into closed circuit position by the action of a relay 104. One terminal 105 of the switch 104 is connected to a terminal 85' of the switch 77' by a wire 106, and the relay 104 is connected across the wires 97' and 106 in operative connection with the terminals 78' and 80', respectively, of the battery 70', whereby upon closing of the trigger switch the relay is energized by the battery current and the switch 101 is closed. The other terminal 107 of the switch 101 is connected by a wire 109 to one terminal 110 of a switch 111 having its other terminal 112 connected to the solenoid 50 by the wire 99'. The switch 111 is normally held in closed circuit position by a spring 114 and is adapted to be moved into open circuit position by the action of a relay 115. The relay 115 has its terminals connected by wires 67' and 68' to suitable means for generating an electric current during the normal movement of the gun, which means may comprise a coil 60, a permanent magnet 61 adapted to reciprocate or oscillate within the coil 60, and a rectifier circuit 66. The magnet 61 is operatively associated with the rider assembly 25 of the bolt or charging mechanism of the gun adapted to reciprocate during normal firing.

The devices of the circuit illustrated in Fig-

ure 4 operate as follows: When the trigger switch 77' is closed to fire the gun, the solenoid 104 is energized by the battery current to close the switch 101 in opposition to its spring 102. As the gun proceeds to fire, the magnet 61 is oscillated or reciprocated with respect to the coil 60, whereby an electric current is generated in the coil, which energizes the relay 115 to move into open position the switch 111 in opposition to its spring 114. When the switches 77', 101 and 111 are in the foregoing described positions, as illustrated in broken lines in Figure 4, current will not flow to the gun charger controlling solenoid 50 and operation of the solenoid is prevented.

In the event the bolt or charging mechanism of the gun slows down or stops, while the trigger switch is being held in closed position, the generating means will fail to provide an electric current altogether or a current of sufficient magnitude to energize the relay 115 to enable it to maintain the switch 111 in open circuit position, whereby the switch 111 is moved into closed circuit position by its spring 114. When this occurs, the solenoid 50 is energized by the battery current flowing through wire 81', switch 77', wire 106, switch 101, wire 109, switch 111 and wire 99'; and, after passing through the solenoid winding returning through wire 97'. As the gun charger restores the bolt or charging mechanism of the gun to normal motion, current is again generated to energize the relay 115 which opens the switch 111, whereby battery current ceases to be supplied to the solenoid 50.

From the foregoing description it will be seen that the present invention provides an improved method and apparatus for controlling gun chargers. The electrical circuits and device therein are simple in construction, and can be economically provided. The parts utilized are light in weight but are adapted to withstand any rough usage to which they may be subjected. Furthermore, the apparatus is adapted to return the gun to firing operation in a minimum period of time.

As various changes may be made in the form, construction and arrangement of the parts herein, without departing from the spirit and scope of the invention and without sacrificing any of its advantages, it is to be understood that all matter herein is to be interpreted as illustrative and not in any limiting sense.

It is also to be understood that the following claims are intended to cover all the generic and specific features of the invention herein described, and all statements of the scope of the invention which, as a matter of language, might be said to fall therebetween.

I claim:

1. In a gun charger for a machine gun having a reciprocating member, the combination with said reciprocating member of a normally inactive charging mechanism for operating the reciprocating member, an electrical control device constructed and arranged to be actuated by a current of a predetermined magnitude for rendering said charging mechanism operative, an energizing circuit including means for supplying said predetermined current to said control device, current generating means adapted to be driven by said reciprocating member, and means constructed and arranged for operation by said generated current to render said energizing circuit ineffective to supply current to said control device during normal operation of said reciprocating member and upon failure of said generated current to permit energization of said con-

trol device by said energizing circuit to thereby effect operation of said charging mechanism.

2. In a gun charger for a machine gun having a reciprocating member, the combination with said reciprocating member of a normally inactive charging mechanism for operating the reciprocating member, an electrical control device constructed and arranged to be actuated by a current of a predetermined magnitude for rendering said charging mechanism operative, an energizing circuit including means for supplying said predetermined current to said control device, current generating means adapted to be driven by said reciprocating member, and means constructed and arranged whereby said generated current opposes said supplied current to render said energizing circuit ineffective to supply current to said control device during normal operation of said reciprocating member and upon failure of said generated current to permit energization of said control device by said energizing circuit to thereby effect operation of said charging mechanism.

3. In a gun charger for a machine gun having a reciprocating member, the combination with said reciprocating member of a normally inactive charging mechanism for operating the reciprocating member, an electrical control device constructed and arranged to be actuated by a current of a predetermined magnitude for rendering said charging mechanism operative, an energizing circuit including means for supplying said predetermined current to said control device, a second circuit, current generating means in said second circuit adapted to be driven by said reciprocating member, and connection means between said second circuit and said control device whereby said generated current opposes said supplied current, whereby said supplied current is ineffective to actuate said control device during normal operation of said reciprocating member and upon failure of said generated current is effective to actuate said control device to thereby effect operation of said charging mechanism.

4. In a gun charger for a machine gun having a reciprocating member, the combination with

said reciprocating member of a normally inactive charging mechanism for operating the reciprocating member, an electrical control device constructed and arranged to be actuated by a current of a predetermined magnitude for rendering said charging mechanism operative, an energizing circuit including means for supplying said predetermined current to said control device, current generating means adapted to be driven by said reciprocating member, and means constructed and arranged for operation by said generated current including switch means to render said first energizing circuit ineffective to supply current to said control device during normal operation of said reciprocating member and upon failure of said generated current to permit energization of said control device by said first circuit to thereby effect operation of said charging mechanism.
